US00D648846S

(12) **United States Design Patent**
Omura et al.

(10) **Patent No.:** **US D648,846 S**
(45) **Date of Patent:** **** Nov. 15, 2011**

(54) **MASK FOR RESPIRATOR**

(75) Inventors: **Keiko Omura**, Hino (JP); **Shinya Fujimoto**, Ibaraki (JP); **Akito Nishijima**, Ibaraki (JP)

(73) Assignee: **Teijin Pharma Limited**, Tokyo (JP)

(**) Term: **14 Years**

(21) Appl. No.: **29/369,646**

(22) Filed: **Sep. 10, 2010**

(30) **Foreign Application Priority Data**

Mar. 12, 2010 (JP) 2010-006121

(51) **LOC (9) Cl.** **29-02**

(52) **U.S. Cl.** **D24/110.1**

(58) **Field of Classification Search** D24/110, D24/110.1, 110.4, 110.5, 110.6, 129, 164, 128/205.29, 205.25, 206.12, 206.13, 206.24, 128/206.19, 206.25, 206.28, 206.18, 207.13

See application file for complete search history.

(57) **CLAIM**

The ornamental design for a mask for respirator, as shown and described.

DESCRIPTION

FIG. 1 is a perspective view of a mask for respirator showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
